UNITED STATES PATENT OFFICE.

EDWARD L. LIEDKE, OF SANDUSKY, OHIO.

CHECK-PUNCH.

SPECIFICATION forming part of Letters Patent No. 407,867, dated July 30, 1889.

Application filed August 13, 1888. Serial No. 282,537. (No model.)

To all whom it may concern.

Be it known that I, EDWARD L. LIEDKE, a citizen of the United States, and a resident of Sandusky, county of Erie, and State of Ohio, 5 have invented certain new and useful Improvements in Check-Punches, of which the following is a specification, the principle of the invention being herein explained and the best mode in which I have contemplated applying that principle so as to distinguish it 10 from other inventions.

The object of my invention consists of the improvements hereinafter described and claimed.

15 Referring to the drawings, Figure 1 is a perspective view of the check-punch. Fig. 2 is a horizontal central sectional view of the punch, certain portions being in plan. Fig. 3 is a vertical central section of the punch. Fig. 4 is a 20 detail view of the ratchet and connections. Fig. 5 is a detail view of the check-holder. Fig. 6 is a perspective view of the punch with the front plates removed. Fig. 7 is a detail view of the punch and the male and female dies. 25 Fig. 8 is a perspective view of the check-plate, a certain portion being broken away.

In the upper horizontal portion A of my punch I journal the vertical spindle B, that has its lower extremity b pivotally supported 30 in the bracket b', that is secured to the back wall of the punch. Integral with said spindle B are, respectively, the upper and lower sectors C C', the former carrying a series of punches c, that have vertically-sliding bearings 35 in openings provided on the outer periphery of said sector. The lower extremities of said punches are respectively provided with male cutting-dies having the characters \$ 1 2 3 4 5 6 7 8 9 0 on their faces c'. These dies 40 respectively interfit with the corresponding female dies c', that are secured to the upper face of the sector C'. Said punches are secured in position by means of set-screws e, that engage with the vertical plain-faced slotted portions e³ of the punches. Said set-screws also act as stops engaging with the shoulder e' of the punches and limit the downward movement of the same. Sector C is of greater thickness at its outer edge, where the 45 punches are inserted, in order to give increased bearing-surface for the punches.

Springs e² have bearing at one extremity in the sector, and at their upper extremity are inserted in openings respectively formed in the punches, and tend to elevate the punches 55 when depressed. Pivoted at one extremity in lug f is the punch-actuating lever F, and working through an opening in the upper face of the machine and pivotally connected with said lever F is the plunger f', inclosed at its 60 upper portion by spiral spring f², that exerts upward pressure against the actuating-lever. The outer extremity of this actuating-lever is provided with finger-knob f³. On either side of the spindle is pivoted the bifurcated rock- 65 ing lever G, that is connected with the actuating-lever by link g, and at its opposite extremity is loosely connected to pawl g', said pawl engaging at its lower extremity with ratchet-wheel g², the latter being secured to 70 shaft h, journaled longitudinally of the check-punch. Said pawl is provided with a spring g³, that, together with the pawl, works through guide-sleeve g⁴ and causes the pawl to be in constant engagement with the ratchet. Cover 75 g⁵ incloses the inner portion of the actuating-lever and connecting parts.

On the forward portion of the shaft h, intermediate of the sector C' and the front wall of the punch, is the friction feed-roller j, rigid 80 with the shaft, and provided with a peripheral face j', formed of india-rubber. Having bearing respectively on opposite sides of said roller is the bifurcated spring j², which maintains said roller steady and prevents undue movement thereof. Face-plate K is provided with the feed-roller opening k and the punch-opening k'. A curved face-plate L is secured vertically to the front of the punch and provided with a vertical guideway l, in which is fitted 90 shank l' of check-holder l'. Spring l² is also fitted in said guideway, and exerts downward pressure on said check-holder. The check-holder is provided with horizontal thumb-piece m, by means of which it may be elevated, and its foot portion is provided with the punch-opening m'. Pivoted also in its lower portion is the idle-roller m², that bears against the friction-roller. To the upper extremity of spindle B is attached knob n and index-finger n', the latter moving along the index-plate n² as the knob n is turned. 95 100

The operation of the punch is readily understood. The check-holder is raised by means of the thumb, and the check to be punched is inserted beneath the same. The force of the 5 spring presses the holder downward onto the check as soon as the hand is removed from the thumb-piece, and the check is securely gripped between the friction-roller and the idle-roller. The index-finger is then turned 10 over the proper character indicated on the index and the actuating-lever depressed, cutting said character on the check. As the lever is raised, there is a certain play of movement between the bifurcated lever and the 15 pawl, which permits the punch to be clear of the paper before the pawl rotates the ratchet, and hence the friction-roller. The index may again be moved and the operation repeated as often as desired until the requisite numbers 20 are cut out of the paper, when the thumb-piece may be elevated and the check removed.

I claim—

1. The combination, with a rotary punch-carrier and a series of punches carried there-by, of pivotal punch-actuating lever F, and punch-engaging plunger f', pivoted to said lever, substantially as set forth.
2. The combination, with rotary vertical spindle B and sectors C C', rigid therewith,

said sector C carrying punches c, said sector 30 C' carrying dies c², said spindle having at its upper end the handle u, of pivotal lever F, lug f, in which the latter is fulcrumed, plunger f', pivoted to said lever, and spring f², substantially as set forth. 35

3. The combination, with rotary vertical spindle B, having knob n on its upper end, sector C, carrying punches c, and sector C', carrying dies c², both said sectors rigid with said spindle, of lever F, plunger f', index-finger n', rigidly secured to said spindle, and index-plate n², substantially as set forth. 40

4. The combination, with pivotal lever F, rocking lever G, and link g, having its opposite extremities respectively pivoted to said two levers, of ratchet g', having its upper end pivoted to lever G by a joint which permits a certain independent play of said two parts, ratchet-wheel g², shaft h, and feed-wheel j', substantially as set forth. 45

In testimony that I claim the foregoing to be my invention I have hereunto set my hand this 23d day of July, A. D. 1888.

EDWARD L. LIEDKE.
